(57) **CLAIM**

The ornamental design for a skillet, as shown and described.

DESCRIPTION

FIG. 1 is a top perspective view of a skillet according to the present invention.

FIG. 2 is a left side view of the skillet of FIG. 1, the right side view being a mirror image thereof.

FIG. 3 is a front view of the skillet of FIG. 1.

FIG. 4 is a rear view of the skillet of FIG. 1.

FIG. 5 is a bottom view of the skillet of FIG. 1; and,

FIG. 6 is a top view of the skillet of FIG. 1.

The dashed lines illustrate a handle and a lifting tab that may be attached to the skillet, and form no part of the claimed design.
